UNITED STATES PATENT OFFICE.

GEORG WILHELM LÖNHOLDT, OF BERLIN, GERMANY.

FIRE-PLACE.

SPECIFICATION forming part of Letters Patent No. 423,693, dated March 18, 1890.

Application filed May 10, 1889. Serial No. 310,213. (No model.)

To all whom it may concern:

Be it known that I, GEORG WILHELM LÖNHOLDT, of Berlin, Germany, a subject of the Emperor of Germany, have invented certain new and useful Improvements in Heating Apparatus, of which the following is a specification.

In grates as at present usually constructed two great evils are found—namely, that the fuel is incompletely burned and that certain parts of the grate itself which come in direct contact with the flame are quickly worn out. The incomplete combustion has the disadvantage that the fuel is partly wasted and that dangerous gases—such as carbonic-oxide gas—are produced, which in stoves and similar grates offer considerable danger to life and health. In consequence of the destructive influence of the fire on parts of the grate these parts have to be made especially strong, and thereby the heat given off at these parts is considerably limited. These evils are avoided by the improvements which form the object of this invention, in which the flame is drawn in downward direction into a fire-proof body and so concentrated that the separate sheets of flame are thoroughly mingled with each other and with a sufficient supply of fresh heated air, so that a complete combustion is effected. By causing the flames to pass downward and concentrating them in a comparatively narrow combustion-chamber the radiating-surfaces in stoves and the heat-absorbing surfaces in boilers that are brought in immediate contact with the flames are protected against injury by burning and the warping of parts of the stove and the opening of the joints are prevented. Even in case of faulty joining of the parts—as, for instance, in Dutch tile ovens—there is no danger from any escape of injurious carbonic-oxide gases, as they are entirely burned, together with other imperfectly-consumed products of combustion, by the intermingling of the flames in the combustion-chamber, and thereby transformed into carbonic acid, which is carried off by the increased draft generated in the stove.

In the accompanying drawings a fire-place with my improvements is shown, Figure 1 representing a vertical transverse section on line $x x$, Fig. 2; and Fig. 2, a horizontal section on line $y y$, Fig. 1.

Similar letters of reference indicate corresponding parts.

In the middle of the grate-bars h is the combustion-chamber a , which is made in tubular and slightly-tapering shape and of fire-proof material. The grate-bars h are divided into two groups, so that a grate at each side of the combustion-chamber is formed. The combustion-chamber a has at its apex a long narrow slot b , called the "combustion-slot." This slot b may with advantage be made tapering—that is to say, narrowing—toward the rear end or exit. The chamber a ends at the base beneath the grate-bars in a tube-shaped portion, the back pipe of which s , Fig. 2, opens out into the chimney, and which can be closed by a damper, while the front portion c of the pipe projects through the front wall of the stove and is closed by a glass pane, or it may serve as an inlet for superheated air or steam into the combustion-chamber, in which case it is suitably shaped for this purpose.

From the rear part of the combustion-chamber extends in downward direction a vertical channel e , which has an opening r for cleaning purposes and which passes through the ash-box. To the channel e are attached circulating-pipes q , for drawing off the combustion-gases, if desired. Over the grate-bars h is suspended the fuel-chamber i , which is made of corrugated boiler-iron, by means of which, when there is a difference of temperature between the fuel-chamber and the mantel of the stove, the latter is preserved against injurious and destructive strains by expansion. This casing i is divided by a channel m , formed by a hollow partition which widens out toward the bottom, and the fuel is prevented from falling thereon by a saddle or deflector o , for which also a tube may be substituted. The sides of the widened part at the ends of the channel m prevent the fuel from falling into the slot b .

The stove may be heated at will, and the pipe s may be used to conduct the furnace-gases direct to the chimney. The flame produced heats at once the walls of the combustion-chamber a , and since the slot b is only of slight width the flames which rush from opposite directions with a powerful draft toward the flue will be forced through the said

slot, so that a complete combustion is effected. This draft is further increased by drawing in the air from above into the furnace through openings controlled by regulating-screws in the supply-door, which will be most natural, as thereby the most direct course is provided for the products of combustion to the chimney. The result of this is that the oxide of carbonic gas generated by the decomposition of fuel in the fire-pot and fuel-chamber cannot accumulate, but is drawn off immediately in downward direction. Further, the downward draft of air through the fuel-chamber and fire-pot, carrying with it the gases developed in the latter, effects a constant cooling of the walls, and especially of the ends of the fuel-chamber, which are thus kept from burning out, this being one of the greatest evils in the stoves as hitherto constructed.

20 When the fire in the stove is thoroughly lighted, the damper may be closed in the flue *a*, so that the gases of combustion produced in the combustion-chamber *a* will pass through the circulating-pipes *q* before reaching the chimney.

Since in this arrangement of the fire-grate the flames do not have any baneful influence either on the mantel of the stove *k* or on the sides of the fuel-chamber, these parts may be 30 made very thin, so that they can emit the heat to greater advantage, which is a valuable consideration in the construction of stoves, as it allows a very advantageous method of heating. The thin hot walls of the fuel-chamber *i* hasten the decomposition and conversion of the fuel into gas, while, as above shown, the complete combustion of the gases takes place in the slot *b* of the combustion-chamber *a*. The combustion-chamber *a* may be single or double walled, and in the latter case the space between the walls may be filled with air or liquid. There may be one or more combustion-chambers in the furnace. In

short, it may be varied at will in its mode of application, material, and position, so long as it answers the above object. It should be kept in mind that the flames are forced downward by the construction of the combustion-chamber and are compressed on passing through the latter.

It is plain that with this arrangement of the grate and fire-pot they can be separated from and located at some distance from the heat-emitting surfaces.

The grate-bars are not necessary for carrying out the invention, for it can be applied to heating apparatuses without bars, since it is mainly by the combustion-chamber that the main object is attained.

Having thus described my invention, I claim as new and desire to secure by Letters Patent—

1. In a heating apparatus, the combination, with a fire-pot, of a combustion-chamber projecting upward from the bottom of the fire-pot and having a slot in the top and a fuel-receptacle located above the fire-pot and having a hollow partition above the combustion-chamber, substantially as set forth.

2. In a heating apparatus, the combination, with a fire-pot, of a combustion-chamber projecting upward from the bottom of the same and having a slot in its top, a fuel-receptacle above the fire-pot, a hollow partition in said fuel-receptacle, which partition is open along the top and bottom and is located above the combustion-chamber, and a deflector above the top of said partition, substantially as set forth.

In witness whereof I have hereunto set my hand in presence of two witnesses.

GEORG WILHELM LÖNHOLDT.
